Patented June 8, 1920.

Fig. 1.

FIG. 2.

FIG. 4.

Fig. 3.

A small, rectangular, striped component with a central hole and a wire attached to it. The component is oriented horizontally, with the wire extending to the right. The stripes are dark and light, alternating in a pattern. There is a small number '18' written in the top right corner of the image.

A diagram of a cylindrical component, likely a handle or a grip. It has a ribbed center section and a smooth outer section. A handle is attached to the right end. The label '13' is on the left, and '17' is on the right end.

UNITED STATES PATENT OFFICE.

ISAAC C. POPPER AND CHARLES H. BAYER, OF NEW YORK, N. Y.

HEATER.

1,342,570.

Specification of Letters Patent.

Patented June 8, 1920.

Application filed July 15, 1918. Serial No. 244,979.

To all whom it may concern:

Be it known that we, ISAAC C. POPPER and CHARLES H. BAYER, citizens of the United States, residing at New York city, in the 5 county of New York and State of New York, have invented certain new and useful Improvements in Heaters, of which the following is a specification.

Our invention relates to an improvement 10 in heaters, and the object is to provide a sheet-metal stove or heater of the so-called "Perfection" type that is adapted for burning a solidified chemical fuel.

Another object is to do away with smoke 15 and the generation of gases and odors, and to provide a heater and burner in which this solidified chemical fuel may be burned and the heat therefrom increased or diminished, and in other words absolutely under the 20 control of the operator.

With these and other possible objects in view, our invention consists in a heater preferably made in sections and having air inlets and outlets at the bottom and top, a can for 25 the fuel, a chimney, and means for controlling the draft through the chimney whereby the intensity of the heat is absolutely controllable and the light capable of being easily extinguished.

30 This invention further consists in constructional details which will be hereinafter described and pointed out in the claims.

In the accompanying drawings:

Figure 1 is a vertical sectional view 35 through the heater, showing all the parts assembled and in place;

Fig. 2 is a view in side elevation of the fuel can and chimney;

Fig. 3 is a view of the chimney alone;

40 Fig. 4 is a view of the two forms of bands used for controlling the air inlets and outlets;

Fig. 5 is a view of the baffle-plate or hood at the top of the chimney.

45 The heater is preferably made of sheet-iron and in two sections hinged together, as shown in Fig. 1. These sections, for convenience, will be designated the base section 1 and the top section 2. The base section is 50 provided with a number of air inlet holes 3, both in the sides and bottom, and this base section is generally mounted on legs 4 to hold it above the floor and allow free cir-

culation of air in through holes 3 to admit oxygen to support combustion. The top section also has holes 5 for the escape of the products of combustion.

A fuel can 6 rests centrally upon the bottom. This contains a solidified chemical fuel, such as solidified wood alcohol, and 60 may be made of suitable size and dimensions to contain a sufficient amount of fuel to burn for several hours, or the time generally required for a heater of this character.

65 The upper edge of this can may be crimped inwardly as shown at 7, or otherwise constructed as found most suitable for the purpose.

The numeral 8 indicates what we term the 70 chimney. This is, in the main, cylindrical in form with an enlarged lower end with an outwardly-curved flange 9 to fit snugly over the crimped upper edge 7 of the fuel can.

75 The length of the chimney is such that it reaches from the top of the fuel can, where its lower end rests, to a point nearly at the top of the heater, where it is provided with a baffle-plate or hood 10 to deflect the heat rising through the chimney, causing its expulsion downwardly and outwardly in contact with the side of the heater, whereby to greatly increase the radiation and intensity of the heat.

80 In order to regulate the combustion through the chimney, two rows of holes are provided, one set 11 in the lower end of the chimney, and the other 12 at its upper end within the area of the baffle-plate or hood. The lower set of holes 11 is for the ingress 90 of air from the base of the heater to support combustion, and the upper set 12 for the escape of the products of combustion beneath and into the area of the baffle-plate or hood, when it is deflected and disseminated 95 throughout the upper area of the heater.

85 The size of the openings 11 and 12 may be controlled in any approved manner, as it is through this medium that the combustion is regulated and controlled. As a simple 100 means for doing this, the bands 13 and 14 are provided. These bands encircle the chimney snugly and are provided with openings 15 and 16 respectively, which correspond with the holes or openings 11 and 105 12 in the chimney, and are adapted to open

or close the same and regulate the size of opening when brought into registry therewith by turning the bands to the right or left, which is accomplished by manipulating the hand-levers 17 and 18 extending outwardly from the bands, as shown in the drawings.

The chimney is secured rigidly in the top section 2 of the stove or heater, and the fuel-can 6 may rest loosely on the bottom of the base section, where it is held firmly in place and centered by the chimney when the top is closed and in its normal position as shown in Fig. 1.

15 By means of this heater, we are enabled to overcome the objection to the use of ordinary coal-oil or kerosene which requires an expensive burner, and which, under the most favorable conditions, is liable to smoke more or less. At the same time, we are able to obtain as much, if not more, intense heat, while the heater is absolutely odorless.

20 The fuel is molded in the can where it may be stored and confined almost indefinitely by keeping the can closed air-tight, so that when the heater is to be used it is simply necessary to open a can of the fuel and place it in the base section, whereupon after touching a match to the open upper 30 end of the can and igniting the fuel (which ignites instantaneously) the top is closed, and it remains to adjust the damper-bands to regulate the amount of heat that is desired.

25 It is obvious that more or less slight changes might be resorted to in the form and arrangements of the several parts described without departure from the spirit and scope of our invention; and hence we 40 do not by any means wish to be limited to

the exact construction herein set forth, but:—

We claim:

1. A heater made in two sections, a can to contain fuel located in the base section, and the top section having a chimney rigidly secured thereto, the lower edge of which fits down upon and holds the can of fuel in place in the base section when the top section is in its normal position. 50

2. A heater made in two sections, a can to contain fuel located in the base section, the top section having a chimney rigidly secured thereto, the lower edge of which fits down upon and holds the can of fuel in place in the base section when the top section is in its normal position, both sections having perforations for the circulation of air and products of combustion, the chimney also perforated, and means for opening and closing and regulating the size of said chimney perforations. 55

3. A heater made in two sections, a can to contain fuel located in the base section, the top section having a chimney rigidly secured thereto, the lower edge of which fits down upon and holds the can of fuel in place in the base section when the top section is in its normal position, both sections having perforations for the circulation of air and products of combustion, the chimney also perforated, means for opening and closing and regulating the size of said chimney perforations, and a baffle-plate or hood over the upper end of the chimney for deflecting the heat rising through the latter. 60

In testimony whereof we affix our signatures.

ISAAC C. POPPER.
CHARLES H. BAYER.
